CIRCUIT BREAKER

Benjamin P. Baker, Turtle Creek, and Herbert L. Rawlins, Pittsburgh, Pa., assignors to Westinghouse Electric & Manufacturing Company, East Pittsburgh, Pa., a corporation of Pennsylvania

Application March 19, 1942, Serial No. 435,381

29 Claims. (Cl. 200—148)

This invention relates to improvements in circuit breakers, and, more particularly, to circuit breakers of the type wherein arc extinction is at least in part effected by subjecting the arc drawn to a blast of arc extinguishing fluid, either liquid or gaseous. More specifically, the present invention concerns improvements in circuit breakers of the aforesaid type which have a pressure chamber in which the arc is drawn, said pressure chamber containing a liquid or gaseous arc extinguishing fluid, means for increasing the pressure of the liquid or gaseous arc extinguishing fluid contained in said pressure chamber to a predetermined pressure, at which time the pressure of the fluid in said pressure chamber is suddenly released to effect extinguishment of the arc and a consequent interruption of the circuit through the breaker.

Our invention is not limited in all of its applications to the utilization of a gaseous arc extinguishing fluid. A liquid fluid may well be used, but for the purpose of illustrating a preferred form of the invention a gaseous fluid is employed in the following specification.

When the present invention is applied to circuit breakers of the type which effect extinguishment of the arc by a blast of a gaseous arc extinguishing fluid, it is possible to have the pressure generating means disposed within the pressure chamber also augment the existing supply of gaseous arc extinguishing fluid contained within the pressure chamber. In other words it is possible to have material disposed within the pressure chamber, which, when subjected to an arc, will evolve additional gaseous arc extinguishing fluid. In this event the supply of gaseous arc extinguishing fluid contained within the pressure chamber will not only be increased, but also the pressure will be raised within the pressure chamber.

When the invention is applied to a liquid type circuit breaker, it is not necessary to furnish a gas evolving solid material within the pressure chamber. The arc acting upon the liquid disposed within the pressure chamber would furnish the required pressure. For purposes of illustration, however, the invention will be described when it is applied to a breaker which utilizes a gaseous arc extinguishing fluid to effect the extinction of the arc.

We have found that the conventional compressed air circuit breaker, which utilizes a nozzle through which the compressed air passes to extinguish the arc drawn in the nozzle, seems to require air pressures which increase rapidly with increased k. v. a. interrupting capacity. The

highest rating now on the market for this type of compressed air circuit interrupter does not exceed 800,000 k. v. a. for power house type of interrupters, and it requires pressures up to 240 pounds per square inch. It is apparent that in order to extend the range of this type of interrupter to 1,000,000 or 1,500,000 k. v. a. interrupting capacity, impractical pressures would be required.

We have observed from the results obtained on 10 a self-generated gas blast type of breaker, which successfully interrupted 48,000 amperes at 7,600 volts and which consisted of a structure which contained a gas generating break and an arc interrupting break, that in order to make the gas evolving structure adequate to interrupt the low currents, the pressure generated during the interruption of high currents was of the order of 1,000 pounds per square inch. Pressures of this order are not only unnecessary, but are dangerous to life and property.

In the following application of our invention, we describe a structure which permits the use of gas at nominal pressures (less than 200 pounds per square inch) for producing mechanical operation of the contacts and interrupting the low and medium values of current. For the interruption of the higher values of current which require still more pressure, we have provided a device incorporated within the interrupter, which generates an augmenting gas supply. Consequently, if low currents are being interrupted, the generated gas will be negligible in comparison with the gas supply furnished by the reservoir used to actuate the breaker. On the other hand, if the current which is being interrupted 25 is of a comparatively high value, the compressed gas will serve to operate the breaker mechanically and then will be cut off by a check valve which closes when the pressure produced by the self-generating device within the breaker exceeds the pressure provided by the external gas source.

One embodiment of our invention also concerns the provision of a self-generating gas type of breaker, which generates gas at one point 30 within the breaker, which gas produces a rise of pressure within the breaker to operate a vent disposed at another point in the housing of the breaker.

The main object of the present invention is to 35 provide a circuit breaker of the aforesaid type, which by virtue of the location of the structural parts thereof will render improved and more effective performance.

A further object of the present invention is 40 to provide a circuit breaker which comprises a

pressure chamber, a liquid or a gaseous arc extinguishing fluid disposed within said pressure chamber, means initiated by an arc drawn within said pressure chamber to raise the pressure of the fluid within said pressure chamber, means responsive to the pressure within said pressure chamber for actuating a vent disposed within a wall of said pressure chamber, said vent causing a blast of arc extinguishing fluid to effect extinguishment of an arc drawn within said pressure chamber.

A more specific object of the present invention is the provision of an improved circuit breaker which has a pressure chamber in which either a liquid or gaseous arc extinguishing fluid is disposed, means external to said pressure chamber for supplying the required amount of arc extinguishing fluid at the proper pressure to effect extinguishment of the low and medium values of current, and means disposed within said pressure chamber for utilizing a series arc on the high values of current to increase the pressure within said pressure chamber to the amount necessary to effect the extinguishment of the higher values of current.

A more specific object of the present invention is the provision of an improved circuit breaker of the aforesaid type which utilizes an external supply of arc extinguishing fluid for low current interruption, but yet on high current interruption utilizes also arc extinguishing fluid generated within the breaker itself, thus resulting in economical breaker performance.

Another object of the present invention is the provision of an improved circuit breaker of the aforesaid type which generates arc extinguishing fluid at one point within the breaker, stores said generated arc extinguishing fluid within a storage chamber until the pressure there is sufficient to interrupt the current passing through the breaker, and then by the actuation of suitable vent means renders said stored arc extinguishing fluid available to effect the interruption of the current at a different point within the breaker.

Another object of the present invention is the provision of an improved circuit breaker of the aforesaid type which generates arc extinguishing fluid within a generating means, stores said generated arc extinguishing fluid until the pressure thereof is sufficient to effect the interruption of the breaker current, and then by the actuation of suitable vent means utilizes said generated fluid to effect circuit interruption at a point in the interior of said generating means.

Another object of the present invention is the provision of an improved circuit breaker which employs either a supply of arc extinguishing fluid furnished exclusively by an external source, or the combination of an external and an internal source of arc extinguishing fluid, said arc extinguishing fluid serving a dual purpose of assisting arc removal and also arc interruption.

Another object of the present invention is the provision of an improved circuit breaker which utilizes a plurality of serially related arcs, one or more of said arcs assisting in the production of arc extinguishing fluid under pressure to effect the interruption of one or more other of said plurality of serially related arcs.

A more specific object of the present invention is the provision of an improved circuit breaker of the aforesaid type which on low current interruption utilizes an external source of arc extinguishing fluid for arc removal and for

arc interruption, and on high current interruption cuts off said external source and utilizes exclusively an internal source of arc extinguishing fluid, thus eliminating the necessity of a high pressure external source for high current interruption.

A specific object is the provision of a circuit breaker which may be used in conjunction with a relatively low pressure external source of arc extinguishing fluid, such as air, for the mechanical actuation of the circuit breaker mechanism and for the extinction of low current arcs, but which provides its own supply of high pressure arc extinguishing fluid for high current interruption.

It is to be clearly understood that in the following description of our invention as applied specifically to circuit breakers of the type which utilize a gaseous arc extinguishing fluid, we do not intend to limit the scope of our invention entirely to gaseous type circuit breakers which are preferred for some applications. Instead of the arc reacting on a gas evolving solid material as in the preferred gaseous type breaker, it could react on a liquid arc extinguishing fluid disposed within the pressure chamber to generate the requisite pressure necessary for arc interruption.

Other objects and advantages will appear more fully in the following description when read in connection with the accompanying drawings, in which:

Figure 1 is a side elevational view, partly in section, of a circuit breaker constructed in accordance with the principles of our invention, and shown in the partly open-circuit position;

Fig. 9 is a side elevational view, partly in section, of another embodiment of our invention, the breaker being shown in the partly open circuit position.

Referring to Figure 1, the reference numeral 1 designates a suitable base plate, preferably of metal, supported upon metal legs 3. The base plate 1 supports a tubular insulator 5 which is secured to an annular flanged support plate 7 which has a centrally disposed aperture 9 there-

in. Threadedly inserted in the centrally disposed aperture 9 is an insulating conduit 11 passing through the tubular insulator 5 and leading to an electrically actuated valve mechanism generally designated by the reference numeral 13. The valve mechanism 13 controls the passage of fluid through the conduit 11 from a storage tank 15, where the fluid is maintained under pressure by suitable means not shown.

The conduit 11 leads through the centrally disposed aperture 9 into a closed (except for vents which will be described hereinafter) longitudinal chamber generally indicated by the reference numeral 17. The longitudinal chamber 17 comprises a longitudinal tubular casing 19 of insulating material, the lower end of which is threadedly secured to the annular flanged support plate 7, and the upper end of which is closed by a flanged annular metallic closure member 21. The flanged annular closure member 21 has a centrally disposed vent 23 therein, which is normally closed by a valve mechanism generally designated by the reference numeral 25, which will be described hereinafter.

A fluid directing baffle 27 is disposed within the closed chamber 17, at the lower end thereof, and this baffle has a centrally disposed aperture 29 therein which serves to direct the fluid coming upwardly through the conduit 11 from the storage tank 15 between a stationary contact 31 and a movable contact 33 when the valve mechanism 13 is actuated. A check valve 35 disposed between the directing baffle 27 and the annular support plate 7 opens when the pressure of fluid in conduit 11 is greater than the pressure of fluid within the closed chamber 17, and closes when the pressure of fluid within the chamber 17 is greater than the pressure of fluid within conduit 11.

The movable contact 33 is actuated to open and closed circuit positions by a crank arm 37 pivoted at 39 to the framework of a piston chamber 41. A piston 43 adapted for reciprocating longitudinal motion within the piston chamber 41 is connected to the crank arm 37, so that when compressed fluid from the storage tank 15 is admitted by an electrically operated valve 45 through a conduit 47 to the piston chamber 41, the resulting upward motion of piston 43 will close the movable contact 33. A compression spring 49 disposed between the upper end of the piston chamber 41 and the piston 43 serves to bias the piston 43 downward and hence to bias the movable contact 33 to the open circuit position.

A latch mechanism generally indicated by the reference numeral 51 serves to latch the crank arm 37 in the closed-circuit position, thus permitting the breaker to be closed and to remain closed by a momentary fluid pulse through the electrically operated valve 45. The latch mechanism may be actuated by a solenoid 53 schematically indicated in Fig. 1.

From the description of the breaker thus far, it is obvious that momentary actuation of the valve mechanism 45 results in closing the breaker, the latch mechanism 51 serving to maintain the breaker in the closed-circuit position. When it is desired to open the breaker, solenoid 53 is electrically actuated thus permitting the bias exerted by the compression spring 49 to open the breaker. The valve mechanism 45 releases the pressure within the piston chamber 41 to permit piston 43 to be moved downward by the compression spring 49.

When the breaker is closed, the electrical circuit consists of a terminal cable 55, terminal stud bolt 57, flexible cable 59, movable contact 33, stationary contact 31, terminal stud 61, and terminal cable 63.

Electrically connected to the terminal stud bolt 57 and disposed within the longitudinal tubular insulating casing 19 adjacent the inner wall thereof and spaced slightly above the movable contact 33 is a metallic arcing horn 65. Diametrically opposite to the arcing horn 65 is a metallic arcing horn 67 spaced by an insulating barrier 69 from the stationary contact 31, and extending upward adjacent the inner wall of casing 19 to a point in the immediate vicinity of vent 23. Here the metallic arcing horn 67 is electrically connected by a flexible conductor 71 to an electrode 73 which is biased by a compression spring 75 to close the vent 23. The electrode 73 is guided in its longitudinal motion by a spider 77 disposed in the upper end of a piston chamber 79, which vents at its other end through a conduit 81 to the atmosphere outside the casing 19. A piston 83 secured to the lower end of the electrode 73 is responsive to the fluid pressure within the casing 19 and is adapted to move downward within the piston chamber 79 against the biasing action of compression spring 75 when high fluid pressure exists in the casing 19. The vent at the back side of the piston 83 through conduit 81 to the outside atmosphere eliminates any back pressure acting upon piston 83.

Disposed within the casing 19 and extending longitudinally thereof are a plurality of relatively thin insulating plate members 85 formed of any suitable material which emits a vapor or gas when exposed to the action of an arc, such as horn fiber, boric acid, etc. The plate members 85 are spaced from each other and are supported by two insulating support members 87 secured by screws 89 to the inner wall of casing 19, as more clearly shown in Fig. 2. Each plate 85 has a wedge-shaped slot 91 therein, as more clearly shown by Fig. 3, the slots aligning when the plates 85 are assembled on the two insulating supports 87 to form an inverted V-shaped arc passage 93, as more clearly indicated in Fig. 1.

A metallic rod 95 extending exteriorly of the casing 19 serves to electrically connect the metallic closure member 21 to the terminal stud 61, the reason for which will appear hereinafter.

The operation of the circuit breaker shown illustrated in Figs. 1, 2 and 3 will now be described together with the method utilized to effect arc extinction. When the breaker is in the closed-circuit position movable contact 33 abuts with stationary contact 31, the latch mechanism 51 maintaining the two contacts 33 and 31 in abutting relation. The pressure within the casing 19 is normal, and hence electrode 73 within the upper portion of the casing 19 is biased by the compression spring 75 to close the vent 23 in the metallic closure member 21. Valve mechanism 13 not being operated, check valve 35 rests upon the flanged support plate member 7, and the electrical circuit through the breaker is as has been previously described, that is terminal cable 55, stud bolt 57, flexible cable 59, movable contact 33, stationary contact 31, stud bolt 61, and terminal cable 63.

When it is desired to open the electrical circuit through the breaker, or when overload conditions exist in the external electrical circuit, solenoid 53 is electrically actuated to release crank arm 37 and to permit compression spring 49 to move crank arm 37 downward, and hence to move mov-

able contact 33 to the left. At the same time that solenoid 53 is electrically actuated, valve mechanism 13 is also actuated to effect the admittance of fluid from the storage tank 15 through the valve mechanism 13, through conduit 11 to the casing 19, which is now closed at its upper end. When movable contact 33 separates from stationary contact 31 an arc will be drawn between the two contacts 33 and 31. The upward rushing fluid from the storage tank 15 will move this drawn arc up past the insulating barrier 69 to the two metallic arcing horns 65 and 67 to the position 90, as shown in Fig. 1. The electrical circuit through the breaker now consists of the following: terminal cable 55, stud bolt 57, metallic arcing horn 65, the arc 90 itself, metallic arcing horn 67, flexible conductor 11, electrode 73 (now closed against vent 23), metallic closure member 21, conducting rod 95, stud bolt 61, and terminal cable 63.

The upwardly rushing fluid from the storage tank 15 through conduit 11 and the check valve 35 builds up the fluid pressure within the casing 19, so that piston 63 responsive to this pressure opens the electrode 73 to draw a second arc between the electrode 73 and the vent or nozzle 23. The electrical circuit now through the breaker is the same as that immediately described above with the exception that there are two arcs in series, one between the arc horns 65 and 67, and a second between electrode 73 and nozzle 23.

The fluid from the storage tank 15 now passes from the lower end of the casing 19 up against the arc drawn between the arcing horns 65 and 67, up between the insulating plates 85, and finally out of the casing 19 through the nozzle 23. This passage of fluid from the tank 15 entirely through the longitudinal casing 19 and out through the nozzle 23 serves to move the arc farther up the arcing horns 65 and 67 to force the arc to intimately engage the insulating plates 85, and hence to evolve vapor or gas from the plates 85 as a result of the direct action of the arc thereon.

Assuming that the current through the breaker to be interrupted is high, the amount of gas or vapor evolved from the plates 85 as a result of the arc playing thereon will correspondingly be high, and will cause the pressure within the casing 19 to rise sufficiently to close the check valve 35. This large amount of evolved gas from the plates 85 as a result of high current through the breaker will pass up through the plates 85, the upper portions of which serve to cool the evolved gas and to deionize the same. In absorbing the heat from the evolved gas the upper portions of the plates 85 give off additional gas or vapor which is at a lower temperature than the gas evolved from the lower portions of the plates 85. Thus during high current interruption gas is generated in the plates 85 first from the direct action of the arc on the lower portion of the plates 85, and secondly as a result of absorption by the upper portions of the plates 85 of the heat contained in the first evolved gas. Thus the current through the interrupter is extinguished at the nozzle 23 of the interrupter.

It will be apparent that we have provided an interrupter which serves to interrupt low and medium values of current by the blast of arc extinguishing gas produced in the storage tank 15, the compressed gas stored in storage tank 15 also serving to operate the contacts of the interrupter. For the interruption of high values of current, the pressure of the gas generated by the

arc on the plates 85 will be sufficient to close the check valve 35 and to extinguish the arc drawn between the electrode 73 and the nozzle 23. It will, therefore, be apparent that the design of the gas generating insulating plates 85 will be facilitated inasmuch as they can be designed to extinguish only the high values of current through the breaker. Consequently, there is a reduction in the deterioration of the gas evolving insulating plates 85 as compared to breakers of the prior art wherein the gas evolving plates had to be designed for the interruption of low and also high values of current. Our construction also results in a minimum of external dimensions for the breaker, and for quicker extinguishing action for the lower and medium currents as a result of the utilization of an external source of compressed gas. It will furthermore be apparent that the external source of compressed gas may be used for the actuation of the contact operating mechanism.

By the provision of gas evolving insulating plates 85, we have provided a safety feature in case of a loss of pressure of the gas stored in storage tank 15. In other words, should the pressure decrease in the storage tank 15 at least the high values of currents will be extinguished as a result of the evolving of gas from the insulating plates 85.

By utilizing an external source of compressed gas and by the provision of an internal source of gas, we have obtained very uniform arcing time over the entire current range of the breaker. Thus the high values of current are extinguished quickly as a result of the large amount of gas evolved in the plates 85, and the lower values of current are also extinguished quickly by the use of the compressed gas stored in the storage tank 15. Compression spring 75 is so designed as not to permit electrode 73 to move away from nozzle 23 unless the pressure of gas within casing 19 is sufficient to interrupt the arc drawn between electrode 73 and nozzle 23.

In the embodiment of our invention illustrated in Fig. 4, there is shown a cylindrical insulating casing 97, the ends of which are closed by insulating closure members 99 and 101 which are threadedly secured to the insulating casing 97. A movable contact 103, actuated by mechanism not shown, engages stationary contact 105 in the closed circuit position of the breaker.

When the breaker is in the closed circuit position, the electrical circuit therethrough consists of the terminal cable 107, terminal stud bolt 109, flexible cable 111, movable contact 103, stationary contact 105, terminal stud 113, and terminal cable 115.

Directly above the movable contact 103 is provided an arcing horn 117 extending longitudinally upward within the insulating case 97. Above the stationary contact 105 is an insulating barrier 104, on the upper side of which is disposed a second arcing horn 119. The arcing horn 119 extends longitudinally upward within the casing 97, and at its upper end is electrically secured to a flexible cable 121, the other end of which is secured to a movable electrode 123. The movable electrode 123 is guided by a bracket 125 for reciprocating longitudinal movement within a piston chamber 129, a piston 127 being secured to the left-hand end of the electrode 123. The piston chamber 129 is internally provided with stops 139 which terminate the motion of the piston 127 at the end of its leftward motion, the rightward motion of the piston 127 being determined by the electrode 123 engaging a metallic

nozzle 141 which is screw threaded into the side wall of the casing 97.

The piston chamber 129 is secured by the stud 131 to the wall of the insulating casing 97 and a vent 140 is provided to relieve any back-pressure on the rear side of the piston 127. Pins 132 secured to the inner wall of the piston chamber 129 support pivotal spring guide rods 137 around which are encircled compression springs 135. The pivoted spring guide rods 137 are provided with slots 136 therein to engage pins 133 secured to the piston 127. Consequently, the piston 127 is biased by the compression springs 135 to cause the electrode 123 to engage and to close the nozzle 141.

It will be noted that by the arrangement of the pivoted spring guide rods 137 with the compression springs 135 engaging the pins 133 secured to the piston 127, the force required to maintain the piston 127 at the end of its left-hand position will be less than that required to initially move the piston 127 toward the left.

A conductor 143 is secured to the nozzle 141 at one end and the other end of the conductor 143 is secured to the terminal stud 113.

Supported on two insulating support members 146, only one of which is shown, and disposed within the casing 97 are a plurality of plates. These plates comprise plates 145 composed of magnetic material interspersed with gas evolving insulating plates 147. Fig. 5 shows the configuration of the plates 147 and 145, it being noted that both of these plates are provided with a wedge-shaped slot 149. When the plates 147 and 145 are assembled in stacked relation on the insulating support members 146, the slots 149 align so as to form an arc chamber 151 disposed directly above the stationary and moving contacts 105 and 103.

The operation of the interrupter will now be explained. When it is desired to open the breaker or when an external overload exists in the circuit connected through the interrupter, suitable contact operating mechanism, not shown, is actuated to move the movable contact 103 to the left, thus drawing an arc between the movable contact 103 and the stationary contact 105. The magnetic field formed about the arc is distorted by the plates 145 composed of magnetic material so that the arc drawn between the movable contact 103 and the stationary contact 105 is forced in an upward direction to be positioned within the arc chamber 151. There the arc reacts on the gas evolving plates 147, which may be composed of horn fiber, boric acid or any other suitable gas evolving material, to generate an arc extinguishing gas which causes the pressure to rise within the insulating casing 97. As the arc reacts on the plates 147 to generate more arc extinguishing gas, the pressure rises to a sufficient value to cause the piston 127 to overcome the biasing action of the compression springs 135 and move to the left, thus drawing a second series arc between the electrode 123 and the metallic nozzle 141.

The electrical circuit through the interrupter now consists of the terminal cable 107, terminal stud bolt 109, arcing horn 117, the arc through the arcing chamber 151, the arcing horn 119, the flexible cable 121, electrode 123, the arc between the electrode 123 and the metallic nozzle 141, the metallic nozzle 141, conductor 143, terminal stud 113 to the terminal cable 115. The electrical circuit through the interrupter is extinguished by the extinction of the arc drawn between the

electrode 123 and the metallic nozzle 141, this being caused by a blast of gas through the metallic nozzle 141. When the piston 127 is moved to the left by the gas pressure stored within the insulating casing 97, it remains in this position until a relatively low value of the pressure within the casing 97, as a result of the pivotal action of the spring guide rods 137.

It will thus be apparent that in Fig. 4 we have shown an interrupter which draws two arcs in series, one of the arcs generating gas within the casing 97 to a pressure sufficient to enable the second arc formed to be extinguished in a metallic nozzle 141. The design of the springs 135 is such that the piston 127 is not actuated to the left until the pressure within the casing 97 is sufficient to interrupt the arc drawn between the electrode 123 and the metallic nozzle 141. It will be observed that the arc drawn between the arcing horns 117 and 119 will evolve gases from the gas evolving plates 147, which gases being hot will upon rising between the plates 147 become cooled and will generate a further supply of gas at the upper ends of the plates 147. Thus the gas first generated is cooled and augmented by the gas which is evolved from the upper ends of the plates 147. The time which elapses between the first generation of gas from the plates 147 and the time the piston 127 is moved by the pressure within the casing 97 to the left is sufficient for the deionization of the gas initially formed by the arc upon the plates 147. Consequently, when the pressure is sufficient to actuate the piston 127 to the left, and hence to draw a second arc between the electrode 123 and the nozzle 141, the gas which is ejected from the casing 97 is cooled and deionized sufficiently to effect a quick extinguishment of the arc drawn between the electrode 123 and the metallic nozzle 141.

In the embodiment of our invention illustrated in Fig. 6, there is shown an insulating casing 155, the ends of which are closed by the insulating closure members 157 and 159. There is provided a movable contact 161 which engages a stationary contact 103 in the closed-circuit position of the interrupter.

In the closed-circuit position of the interrupter the electrical circuit through the interrupter 50 consists of the terminal cable 165, terminal stud bolt 167, flexible cable 169, movable contact 161, stationary contact 163, magnetic blow-out coil 171, to terminal cable 173. A laminated iron core 175 is disposed within the blow-out coil 171, the ends of the laminated iron core 175 being attached to magnetic pole pieces 177.

Directly above the movable contact 161 is an arcing horn 179. Above the stationary contact 163 is a second conducting arcing horn 181. Supported by insulating support members 186 and disposed within the insulating case 155 are a plurality of gas evolving insulating plates 185, which may be formed of horn fiber, boric acid, or other material which evolves a vapor or gas upon being subjected to an arc. The configuration of the gas evolving plates 185 is more clearly shown in Fig. 8. The gas evolving plates 185 are provided with a wedge-shaped slot 187. When the plates 185 are assembled in stacked relation between the insulating support members 186, the slots 187 form an arcing chamber generally indicated by the reference numeral 189.

Disposed in the upper end of the insulating casing 155 is a piston 197 guided by bracket 195 which is biased by a compression spring 195 to

cause a stem 191 to close a vent 193 formed in a side of the casing 155. The piston 197 moves within the piston chamber 129 which is secured by a stud 131 to a wall of the casing 155, a vent 140 being provided to relieve back-pressure on the left side of the piston 197. A stop 199 is provided for the piston 197. The compression spring 195 thus biases the piston 197 to the right, as viewed in Fig. 6, to close the vent 193 in the insulating casing 155.

The operation of the interrupter will now be explained. When it is desired to open the interrupter to break the current passing therethrough, or when an overload exists in the external circuit connected to the interrupter to result in an actuation of an externally provided trip mechanism, suitable contact operating mechanism, not shown, is actuated to move the movable contact 161 to the left away from the stationary contact 163. The arc thus drawn between the movable contact 161 and the stationary contact 163 is moved by the blow-out coil 171 upwards onto the arcing horns 179 and 181. The arc, the position of which is indicated by the reference numeral 183 in Fig. 6, moves upwards to the upper ends of the arcing horns 179 and 181 into the arcing chamber 189. Within the arcing chamber 189 the arc reacts upon the gas evolving plates 185 to generate a gas. The gas so evolved raises the pressure within the insulating casing 155. There is provided sufficient space between the plates 185 and the lower closure member 159 so that the gas generated within the plates 185 is accumulated in this storage space, indicated generally by the reference numeral 186. When the pressure within the insulating casing 155 has raised sufficiently to move the piston 197 to the left against the biasing action of the compression springs 195, the stem 191 moves away from the vent 193 to permit the ejection from the insulating casing 155 of the accumulated gas stored in the storage space 186.

When the vent 193 opens, the accumulated gas stored in the storage space 186 rushes rapidly upward through the arc drawn at the upper ends of the arcing horns 179 and 181 and out of the insulating casing 155 through the vent 193 to extinguish the arc drawn at the upper ends of the arcing horns 179 and 181. The compression spring 195 is so designed as to remain compressed until the gas pressure within the insulating casing 155 falls to a low value.

It will thus be seen that in the embodiment of our invention illustrated in Fig. 6, we have provided means for drawing an arc between a movable and a stationary contact, blowing the arc upwards by means of a magnetic blow-out coil 171 along a pair of arcing horns 179 and 181 into an arcing chamber 189, wherein gas is generated and stored below the arcing chamber 189 to a pressure sufficiently high to blast upwards through the plates 185 to extinguish the arc drawn therein when the piston 197 moves to the left to open the vent 193 in the wall of the casing 155. Fig. 7, which is a fragmentary transverse cross-sectional view taken substantially along the lines VII—VII in Fig. 6, and in the direction of the arrows, shows the disposition of the plates 185 within the casing 155. It will be apparent in Fig. 6, as was also true in Fig. 4 and Fig. 1, that the gas initially generated in the gas evolving plates 185 is cooled by the upper ends of the plates 185 and in cooling evolves still more gas. It will furthermore be apparent that the

time which is required before the pressure rises sufficiently within the casing 155 to actuate the piston 197 to the left is sufficient to permit a recombination of the ions initially formed. The storage space 186 is purposely provided below the plates 185 so that upon actuation of the piston 197 and the consequent opening of the vent 193, the gas will rush from the storage space 186 upwards through the arcing chamber 189 to extinguish the arc which is positioned therein.

Fig. 9 is another embodiment of our invention, and it incorporates the movable contact operating mechanism of Fig. 1 with the utilization of a pressure chamber similar to that of Fig. 6. The method of operation of the movable contact mechanism is identical to that already described in connection with Fig. 1. The method of arc extinction is also similar to that already described in connection with Fig. 6. However, as will be apparent, an external supply of arc extinguishing gas is furnished by the storage tank 15. The check valve 35 in Fig. 1 has been omitted in Fig. 9. A vent hole 199 is provided at the upper end of the pressure chamber 155.

Since the method of moving the movable contact 161 is identical to that already described in Fig. 1, a further description seems unnecessary. It suffices to say that upon the movement of movable contact 161 to the left to draw an arc between the movable contact 161 and the stationary contact 163 this arc is forced upwards between the two arcing horns 179, 181 by the combined action of the magnetic blow-out coil 171 and also by the admission of arc extinguishing fluid from the storage tank 15 upwards through the vent 201. The magnetic blow-out coil 171 could be omitted, for the blast of arc extinguishing fluid upward from the conduit 11 would be sufficient to raise the arc upwards between the arcing horns 179 and 181 into the arcing chamber 189. As already described in connection with Fig. 6, the arc reacts upon the gas evolving insulating plates 185 to generate gas, which gas together with the gas coming upwards through the conduit 11 is stored in the gas storage region 186 positioned below the insulating plates 185. When the pressure within the casing 155 is sufficient to extinguish the arc in the stack of plates 185, the biasing action of the compression spring 195 will be overcome by the pressure within the casing 155, and the piston 197 will move to the left opening up vent hole 193. When this occurs, the gas stored below the plates 185 will rush upwards through the plates 185 and will extinguish the arc therein.

It will be observed that for the low and medium values of current the amount of gas generated from the plates 185 may be relatively small. In this event the pressure supplied by the storage tank 15 will be sufficient to actuate the piston 197 and to extinguish the arc in the stack of plates 185, the gas in this case being stored in the storage region 186 until actuation of the piston 197 to the left. For the higher values of current, on the other hand, the amount of gas generated within the plates 185 will be relatively large and the gas will again be stored in the storage region 186 until actuation to the left of piston 197, at which time the vent 193 will be opened and the gas will rush upwards through the plates 185 to extinguish the arc therein. The vent 199 may be omitted but if provided it serves to regulate the pressure within the chamber 155.

Where the advantages of a dry-type device are not required an arc extinguishing liquid can be

used in any of the breakers described thus far. Instead of the arc reacting on a gas evolving solid, the arc could react upon a liquid disposed in the pressure chambers in the various breakers to raise the pressure therein and to actuate the respective pistons. By our describing our invention as applied to compressed gas circuit interrupters, we do not mean to limit the scope of our invention to gas type breakers, except where specifically claimed, but intend by the following claims to indicate the scope of our invention.

When the term "arc extinguishing fluid" is used in the specification and in the claims, such term is meant to include a liquid as well as a gaseous arc extinguishing fluid.

Although we have shown and described certain specific embodiments of our invention, we are fully aware that many modifications thereof are possible. Our invention, therefore, is not to be restricted except insofar as is necessitated by the prior art and the spirit of the appended claims.

We claim as our invention:

1. In a circuit interrupter, means defining a substantially closed chamber, means for establishing an arc within said chamber, a plurality of slotted plates disposed within said chamber capable of evolving a gas upon being engaged by an arc, means for causing said arc to move into the slots of said plates thereby engaging the plates to assist raising the pressure within said chamber, venting means for relieving the pressure within said chamber, and opening means for said venting means responsive to the pressure within said chamber.

2. In a circuit interrupter, a substantially closed pressure chamber, arc extinguishing fluid disposed within said pressure chamber, means for establishing an arc within said pressure chamber, a plurality of spaced slotted plates disposed within said chamber capable of evolving a vapor upon contacting an arc, means for causing said arc to move into the slots of said plates thereby contacting the plates to assist raising the pressure within said pressure chamber, and venting means for relieving the pressure within said chamber.

3. In a circuit interrupter, means defining a substantially closed chamber, a plurality of plates disposed within said chamber capable of evolving a gas upon being engaged by an arc, means for establishing at least two serially related arcs within said chamber, at least one of said established arcs being established first, means for causing said first established arc to engage said plates to form gas and hence to assist raising the pressure within said chamber, and means for assisting the extinguishment of at least one of said later established arcs by the increased pressure within said chamber.

4. In a circuit interrupter, a substantially closed chamber, arc extinguishing fluid disposed within said chamber, a plurality of spaced slotted plates disposed within said chamber capable of evolving a vapor upon contacting an arc, means for establishing a plurality of serially related arcs within said chamber, one of said arcs being established prior to the formation of another of said arcs, means for causing at least one of said first established arcs to engage said slotted plates to assist raising the pressure within said chamber, and means for utilizing the raised pressure within said chamber to assist in the extinguishment of one of said later established arcs.

5. In a circuit interrupter, a substantially closed pressure chamber, venting means for said

pressure chamber operable upon a predetermined pressure within said pressure chamber, means for establishing one or more arcs within said chamber, a plurality of spaced plates disposed within said pressure chamber capable of evolving a gas upon being contacted by an arc, means for causing one of said arcs to engage said plates to assist raising the pressure within said pressure chamber, and means for utilizing at least a part of the evolved gas to assist in the extinguishment of one of said arcs.

6. In a circuit interrupter, a substantially closed chamber, means for establishing one or more arcs within said chamber, a plurality of slotted plates disposed within said chamber capable of evolving a gas upon being contacted by an arc, means for causing at least one of said arcs to move into the slots of said plates to assist raising the pressure within said chamber, and means for utilizing at least a part of the gas so evolved by the action of said one or more arcs reacting on said plates to assist in the extinguishment of the electrical circuit passing through said interrupter, said last-mentioned means comprising pressure relieving means responsive to the pressure within said chamber.

7. In a circuit interrupter, means defining a substantially closed pressure chamber, means for establishing a plurality of arcs within said chamber, a material disposed within said chamber capable of evolving a gas upon being contacted by an arc, means for causing at least one of said arcs to engage said material to assist raising the pressure within said pressure chamber, and means for feeding arc extinguishing gas under pressure from an external source into said pressure chamber dependent upon the pressure therein to assist in extinguishing another of said arcs.

8. In a circuit interrupter, means defining a substantially closed pressure chamber, an arc extinguishing fluid disposed within said chamber, a plurality of slotted gas evolving plates, means for establishing one or more arcs within said chamber to assist raising the pressure within said chamber by moving into the slots of said plates, and means for feeding arc extinguishing fluid under pressure from an external source into said chamber dependent upon the pressure therein.

9. In a circuit interrupter, means defining a substantially closed pressure chamber, venting means for said pressure chamber responsive to the pressure therein, an arc extinguishing fluid disposed within said chamber, means for establishing one or more arcs within said chamber to assist raising the pressure within said chamber, an external source of arc extinguishing fluid under pressure, and means for feeding arc extinguishing fluid under pressure from said external source into said chamber upon a circuit opening operation of said interrupter.

10. In a circuit interrupter, means defining a substantially closed pressure chamber, arc extinguishing fluid disposed within said pressure chamber, means for establishing one or more arcs within said pressure chamber, means for causing at least one of said arcs to raise the pressure within said chamber, venting means for relieving the pressure within said chamber, opening means for said venting means responsive to the pressure within said chamber, and means responsive to the pressure within said chamber for permitting the feeding of arc extinguishing fluid under pressure from an external source into said chamber.

11. In a circuit interrupter, means defining a

substantially closed pressure chamber, arc extinguishing fluid disposed within said pressure chamber, means for establishing two or more serially related arcs within said pressure chamber, an external source of arc extinguishing fluid under pressure, means for utilizing at least one of said arcs to assist raising the pressure within said chamber, means for introducing into said chamber arc extinguishing fluid under pressure from said external source, and means for utilizing both the pressure from said external source and also the pressure generated by said one arc within said chamber to assist in the extinguishment of the electrical circuit passing through said interrupter.

12. In a circuit interrupter, means defining a substantially closed pressure chamber, arc extinguishing fluid disposed within said pressure chamber, an external source of arc extinguishing fluid under pressure, means for establishing one or more arcs within said pressure chamber, means for utilizing at least one of said established arcs to assist in raising the pressure within said pressure chamber, means for introducing arc extinguishing fluid under pressure from said external source into said pressure chamber, means for causing the pressure of the introduced arc extinguishing fluid to primarily extinguish the electrical circuit through said interrupter during relatively low values of current, means for causing the raised pressure created by said one or more arcs to primarily extinguish the electrical circuit through said interrupter during relatively high values of current, and venting means for said chamber responsive to the pressure therein.

13. In a circuit interrupter, means defining a substantially closed pressure chamber, arc extinguishing fluid disposed within said pressure chamber, an external source of arc extinguishing fluid under pressure, means for establishing one or more serially related arcs within said pressure chamber, means for causing at least one of said serially related arcs to raise the pressure within said chamber, means responsive to the pressure within said chamber for permitting the introduction of arc extinguishing fluid under pressure from said external source into said chamber, and venting means for said pressure chamber responsive to the pressure therein.

14. In a circuit interrupter, means defining a substantially closed pressure chamber, arc extinguishing fluid disposed within said pressure chamber, an external source of arc extinguishing fluid under pressure, means for establishing one or more arcs within said pressure chamber, means for causing at least one of said arcs to raise the pressure within said pressure chamber, means responsive to the operation of said interrupter to introduce arc extinguishing fluid under pressure from said external source into said chamber, means for causing the pressure of the introduced arc extinguishing fluid to primarily extinguish the electrical circuit through said interrupter during relatively low values of current, means for causing the raised pressure created by said one or more arcs to primarily extinguish the electrical circuit through said interrupter during relatively high values of current, and venting means for said pressure chamber responsive to the pressure therein.

15. In a circuit interrupter, means defining a substantially closed chamber, means for establishing two or more serially related arcs within said chamber, a plurality of spaced plates disposed within said chamber capable of evolving a

gas upon being subjected to an arc, means for causing at least one of said arcs to contact said plates to raise the pressure within said chamber, and venting means adjacent at least one of said serially related arcs for relieving the pressure within said chamber.

16. In a circuit interrupter, means defining a substantially closed chamber, means for establishing two or more serially related arcs within said chamber, a plurality of spaced slotted plates disposed within said chamber capable of evolving a gas upon being contacted by an electric arc, means for causing at least one of said serially related arcs to move into the slots in said plates to raise the pressure within said chamber, venting means disposed adjacent to at least one of said serially related arcs, and means for venting at least a part of the gas stored within said chamber through said venting means to assist in the extinguishment of said one or more arcs disposed adjacent thereto.

17. In a circuit interrupter, means defining a substantially closed chamber, means for establishing two or more serially related arcs within said chamber, a plurality of plates disposed within said chamber capable of evolving a gas upon being contacted by an electric arc, means for causing at least one of said serially related arcs to contact said plates to raise the pressure within said chamber, venting means responsive to the pressure within said chamber disposed adjacent to at least one of said arcs, said venting means being operative to cause a blast of gas out of said chamber to result in the extinguishment of the arc disposed adjacent thereto.

18. In a circuit interrupter, means defining a substantially closed pressure chamber, arc extinguishing fluid disposed within said pressure chamber, an external source of arc extinguishing fluid under pressure, means for establishing two or more serially related arcs within said pressure chamber, venting means for said pressure chamber responsive to the pressure therein, said venting means disposed adjacent to at least one of said arcs, means for causing at least one of said arcs to raise the pressure within said pressure chamber, means responsive to the operation of said interrupter to introduce arc extinguishing fluid under pressure from said external source into said chamber, said arc extinguishing fluid under pressure from said external source discharging from said pressure chamber through said venting means to primarily extinguish said one or more serially related arcs disposed adjacent to said venting means during relatively low values of current, the increased pressure created by said one or more serially related arcs serving primarily on relatively high values of current to extinguish said one or more serially related arcs disposed adjacent to said venting means.

19. In a compressed gas circuit interrupter, a closed chamber, means for establishing two serially related arcs within said chamber, venting means for said chamber responsive to the pressure therein, a material disposed within said chamber capable of evolving a gas upon contacting an arc, said material being provided in the form of a plurality of spaced plates, one of said arcs being drawn adjacent to said plates, the other of said arcs being formed adjacent to said venting means upon the operation thereof, an external supply of arc extinguishing gas under pressure, means responsive to the operation of said interrupter for introducing gas from said external source into said chamber, said introduced

gas blowing the arc formed adjacent to said plates into intimate engagement with said plates to increase the pressure within said chamber, means for cutting off the external supply of gas if the generated gas is sufficient to interrupt said arc drawn upon the operation of said venting means, the rising pressure within said chamber actuating said venting means at a predetermined pressure, the discharge of the gas through said venting means causing an interruption of the arc drawn adjacent thereto.

20. In a circuit interrupter, a closed chamber, venting means for said chamber responsive to the pressure therein, a plurality of spaced insulating plates formed of a material which evolves a gas when contacting an arc, means for establishing two serially related arcs within said chamber, one of said arcs being moved adjacent to said plates, means for causing said arc to intimately engage said plates to raise the pressure within said chamber, the other of said serially related arcs being drawn adjacent to said venting means upon the operation thereof, the operation of said interrupter being such that the increased pressure resulting from the generation of gas from said plates is sufficient to actuate said venting means to draw said arc adjacent thereto and to extinguish the same by a discharge of the gas from said chamber out through said venting means.

21. In a circuit interrupter, means defining a substantially closed chamber, means for establishing an arc within said chamber, a plurality of insulating plates formed of a material which evolves a gas upon contacting an arc, means for causing said arc to engage said plates to generate gas to raise the pressure within said chamber, venting means for said chamber actuated upon a predetermined pressure therein, a gas storage space within said chamber so positioned that the stored gas must traverse said plates before discharging from said chamber through said venting means, the discharge of said stored gas upon the actuation of said venting means causing an extinction of said arc when it is positioned adjacent said plates.

22. In a circuit interrupter of the gas-blast type, a substantially closed chamber, means for establishing an arc within the chamber, a plurality of insulating plates composed of gas-evolving material, an external source of compressed gas, and means for feeding compressed gas from the external source into the chamber to force the arc against the plates to cause thereby emission of evolved gas.

23. In a circuit interrupter of the gas-blast type, a substantially closed chamber, means for establishing an arc within the chamber, a plurality of insulating plates composed of gas-evolving material, an external source of compressed gas, and means responsive to the pressure within the chamber for feeding compressed gas from the external source into the chamber to force the arc against the plates to cause thereby emission of evolved gas.

24. In a circuit interrupter of the gas-blast type, a substantially closed chamber, means for establishing an arc within the chamber, a plurality of insulating plates composed of gas-evolving material, an external source of compressed gas, means for feeding compressed gas from the external source into the chamber to force the arc against the plates to cause thereby emission of

evolved gas, and venting means for the chamber opened upon the attainment of a predetermined pressure therein.

25. In a circuit interrupter of the gas-blast type, a substantially closed chamber, means for establishing an arc within the chamber, a plurality of insulating plates composed of gas-evolving material, an external source of compressed gas, means responsive to the pressure within the chamber for feeding compressed gas from the external source into the chamber to force the arc against the plates to cause thereby emission of evolved gas, and venting means for the chamber opened upon the attainment of a predetermined pressure therein.

26. In a circuit interrupter of the gas-blast type, a substantially closed chamber, means for establishing an arc within the chamber, a plurality of insulating plates composed of gas-evolving material, an external source of compressed gas, means for feeding compressed gas from the external source into the chamber to force the arc against the plates to cause thereby emission of evolved gas, venting means for the chamber opened upon the attainment of a predetermined pressure therein, and means for drawing a second serially related arc adjacent the venting means.

27. In a circuit interrupter of the gas-blast type, a substantially closed chamber, means for establishing an arc within the chamber, a plurality of insulating plates composed of gas-evolving material, an external source of compressed gas, means responsive to the pressure within the chamber for feeding compressed gas from the external source into the chamber to force the arc against the plates to cause thereby emission of evolved gas, venting means for the chamber opened upon the attainment of a predetermined pressure therein, and means for drawing a second serially related arc adjacent the venting means.

28. In a circuit interrupter of the gas-blast type, a substantially closed chamber, means for establishing an arc within the chamber, a plurality of insulating plates composed of gas-evolving material, an external source of compressed gas, means for feeding compressed gas from the external source into the chamber to force the arc against the plates to cause thereby emission of evolved gas, venting means for the chamber opened upon the attainment of a predetermined pressure therein, means for drawing a second serially related arc adjacent the venting means, and the latter arc being extinguished by a blast of gas through the venting means.

29. In a circuit interrupter of the gas-blast type, a substantially closed chamber, means for establishing an arc within the chamber, a plurality of insulating plates composed of gas-evolving material, an external source of compressed gas, means responsive to the pressure within the chamber for feeding compressed gas from the external source into the chamber to force the arc against the plates to cause thereby emission of evolved gas, venting means for the chamber opened upon the attainment of a predetermined pressure therein, means for drawing a second serially related arc adjacent the venting means, and the latter arc being extinguished by a blast of gas through the venting means.
